[57] ABSTRACT

The present invention provides an improved feed mechanism of a coil winding machine having a roller with a sharp edge to contact with pressure a feed shaft which rotates at a constant speed. The roller is mounted at a lower end of a vertical shaft in a traveler which moves along an axis of the feed shaft. The vertical shaft is supported rotatably by the traveler and has a guide grooved pulley to guide a metallic wire. The roller moves on the feed shaft spirally together with directional deviation of the grooved pulley caused from a minute change of winding direction of the metallic wire on a bobbin owing to a natural habit of the metallic wire to be wound as the traveler moves gradually, such that when finishing the winding of layer a coil layer obliqueness of the roller is reversed in compliance with the natural habit of the metallic wire so as to reverse the moving direction of the traveler.

FEED MECHANISM FOR COIL WINDER

BACKGROUND OF THE INVENTION

Generally when metallic wires are to be wound up for coils on a bobbin with regularly wound layers, it is necessary to employ a certain feed mechanism to control the feeding speed of wire according to a prescribed constant feeding speed.

However, wires have an inconstant thickness so that if, for example, there is a minute difference of 0.1 mm for a standard thickness, it will result in a total difference of 1 mm during winding for 10 cm under constant feed, which will make a certain gap or an overpile on the bobbin.

Former feed mechanisms have not attained regular winding layers of coils on the bobbin practically.

The present invention provides an improved feed mechanism of a coil winding machine in which it is not necessary artificially to adjust feed gap or double winding which will result from changes of thickness of the wires or size of the bobbin as well as making it possible to reverse automatically owing to a natural habit of the wire so that the winding coils to be produced will have a most exact and regular arrangement with a tight series of winding.

BRIEF SUMMARY OF INVENTION

The present invention provides an improved feed mechanism which enables the wires themselves to choose and adjust their feed properly for strictly regularly winding layers on the bobbin naturally always in sensitive response to their thickness.

The present invention provides an improved feed mechanism to feed the wires continuously to the bobbin with reversal from one end to another end of the bobbin and vice versa in alternation for producing exactly regular winding layers of the coils under delicate control of feed in compliance with variation of inconstant thickness of the wires or a size of the bobbin.

BRIEF DESCRIPTION OF DRAWINGS

FIG. 1 is a top plan view of a feed mechanism of a coil winding machine of the present invention;

FIG. 2 is a cross-section of an essential mechanism thereof;

FIG. 3 is a front elevation partly in section of FIG. 2; and

FIG. 4 is a top plan view of another embodiment thereof.

DETAILED DESCRIPTION OF INVENTION

FIG. 1 shows a main shaft 1 horizontally mounted on a pedestal 2 which carries a sub-pedestal 2a.

A multi-stage pulley 3 is fixed at the left end of the main shaft 1 to connect with a prime mover (not shown).

Medial pulleys 4, 5 are fixed at a medial position of the main shaft 1.

A feed shaft 6 is mounted horizontally also on the subpedestal 2a in parallel with the main shaft 1.

Pulleys 7, 8 fixed at the feed shaft 6 are opposed to and connected with the medial pulleys 4, 5 through a belt 9 so that rotation of the main shaft 1 is transmitted to the feed shaft 6.

A traveler 10 is mounted slidably at the feed shaft 6 possibly to move right or left on the feed shaft 6 owing to later mentioned reasons.

5 A pair of upper and lower rollers 11, 12, in FIG. 2 and 3, are mounted on the back side of the traveler 10 and sandwich a guide shaft 13 fixed on the sub-pedestal 2a in parallel with the feed shaft 6 to hold and rotate along the guide shaft 13.

10 Four guide grooved pulleys 14, 15, 16, 17 are supported by the traveler 10 and guide a metallic wire a in its winding direction on a bobbin (not shown) riding on the main shaft 1.

15 A supporting pillar 18 is fixedly mounted on the traveler 10 and has a long slot 19 at its upper part, which receives and fixes a supporting plate 20 both ends of which support the pulleys 14, 15, possibly to adjust the height of the supporting plate 20 up or down in the long slot 19.

20 A long slot 21 is also formed in the supporting plate 20 for fixing adjustably the pulleys 14, 15.

25 A vertical shaft 22 is mounted rotatably at the traveler 10 and inserts itself into a cradle 23 which carries the guide grooved pulley 16 and which connects with an adjustable fixture 24 carrying the guide grooved pulley 17. The adjustable fixture 24 is mounted at the cradle 23 by a pin 25.

30 A semi-circular slot 26 is formed in the adjustable fixture 24 and supported at the cradle 23 by the pin 25.

35 A screw 27 is screwed into the cradle 23 and inserted in the semi-circular slot 26 so that the guide grooved pulley 17 can be positioned and stabilized at a desired angle.

40 A long slot 28 is formed in the adjustable fixture 24 so as to adjust a fixing position of the guide grooved pulley 17.

45 A hole 29 is formed in the traveler 10 and receives a bearing case 30 having a cover 31. The bearing case 30 and the cover 31 contain vertical bearings 32, 33 and a horizontal bearing 34 which enable the vertical shaft 22 smoothly to rotate.

50 A roller 35 is supported by a supporter 36 fixed at the lower end of the vertical shaft 22. The roller 35 has a peripherally sharp and conic-sectional edge.

55 A spring 37 connects with the traveler 10 through a pin 38, a recess part 39 receiving the feed shaft 6 and a carrier 40. Both ends of the spring 37 are caught by a lower hook 41 screwed into the carrier 40 and an upper hook 42 screwed into an upper part of the traveler 10 to be bridged between both hooks 41 42 so that to add spring force to the roller 35 as the edge of the roller 35 always contacts on the feed shaft 6 with constant pressure. The recess part 39 is borne by the carrier 40.

60 A projecting rod 43 is jutted out of the back side of the cradle 23 and sandwiched between adjustable screw rods 44, 45 in FIG. 1, the left end of the adjustable screw rod 44 and the right end of the adjustable screw rod 45 contacting both sides of the projecting rod 43 adjustably to set a position of the cradle 23 with respect the feed shaft 6 so that positions of the guide grooved pulleys 16, 17 can also be adjusted. The adjustable screw rods 44, 45 are screwed into a shaft bearer 46 mounted on a shoulder 22a of the vertical shaft 22 directly below the cradle 23.

65 Long holes 47, 47 are formed in the left and right parts of the sub-pedestal 2a and received bolts 48, 48.

In another example shown in FIG. 4, there is a motor 49 mounted on the sub-pedestal 2a.

Pulleys 50, 51 are connected with the motor 49.

A belt 9a is set on the pulley 7 or the pulley 8 fixed at the feed shaft 6 and the pulley 50 or the pulley 51 also, so that the feed shaft 6 is rotated by the motor 49.

Accordingly the sub-pedestal 2a can be controlled to slide before and behind on the pedestal 2 under situation of rotatability of the feed shaft 6 without any change of length of the belt 9a.

Further a control handle 52 is fixed to the right end of pin 38, as viewed in FIG. 3, this pin 38 being supported for rotary movement by a bracket fixed to the remainder of the traveler 10 and shown in FIG. 2 just to the left of the carrier 40 which is urged by the spring 37 in a counterclockwise direction, as viewed in FIG. 2, together with the pin 38 and the handle 52 with respect to the remainder of the traveler 10. When the control handle 52 is swung clockwise, as viewed in FIG. 2, the recessed part 39 will move downwardly away from the feed shaft 6 so that the traveler 10 can be easily adjusted to move to any position along the feed shaft 6.

Symbols 53, 53 designate set screws for determining the position of cradle 23 on shaft 22 and for determining the position of bearing case 30 on traveler 10.

Functionally and mechanically explaining the mentioned embodiments of the feed mechanism of the present invention, the metallic wire a is threaded along the guide grooved pulleys 14, 15 16 and 17, while the cradle 23 having the guide grooved pulleys 16, 17 is swingable in the traveler 10 together with the sharp edge of the roller 35 below the vertical shaft 22 contacting the feed shaft 6 under constant spring pressure.

The metallic wire (or the enameled wire) a leads from a spool (not shown) to the pulley 17 with a brake shoe of felt or the like acting on the spool to control rotation of the spool.

The wire a also passes over the pulleys 16, 15, 14 and is pulled by the bobbin mounted on the main shaft 1.

One revolution of the bobbin with one revolution of the main shaft 1 further pulls and winds up one convolution or winding of the wire a.

Next revolution of the bobbin tends to make next convolution or winding engage the first convolution of the wire a but the next convolution will always slip to a position next to the first convolution owing to its slippery metallic surface and its tension so that this results in two neighbor convolutions, which will cause a certain deviation of both pulleys 16, 17 from the neutral position as shown in FIG. 3 owing to pulling tension of the wire a while slightly changing its winding direction.

Therefore the vertical shaft 22 and the supporter 36 also deviate so that the edge of the roller 35 contacts obliquely on the feed shaft 6. It will be noted from FIGS. 2 and 3 in particular that the groove of the pulley 16 and the sharp edge of the roller 35 are located in a common plane which contains the axis of the swivel shaft 22 with this latter axis perpendicularly intersecting and extending across the axes of the pulley 16 and roller 35.

Then rotation of the feed shaft 6 will make the roller 35 rotate to an oblique direction with respect to the axis of the feed shaft 6 so that the traveler 10 advances gradually on the feed shaft 6 to the right in FIG. 1 and 4 a movement of the traveler 10 is somewhat late with respect to movement of winding part of the wire a.

This movement of the traveler 10 to the right depends upon reaction of the starting end flange of the bobbin against wire a to deviate wire direction.

Winding operation continues to the other end flange 5 of the bobbin which stops further winding while tendency of double winding of the wire a at the other end flange will cause its upper part to slip down to the back adjacent position of its lower part owing reaction of the other end flange and its slippery surface as also before 10 mentioned, so that the wire winding direction will reverse and the winding operation continues with a return pass so as to make a new upper layer series of convolutions of the wire a on the next lower layer thereof tightly.

15 These forward and return winding operations repeat alternately between the both end flanges of the bobbin.

The vertical bearings 32, 33 are antifrictional to the horizontal direction and the horizontal bearing 34 is 20 antifrictional to the vertical direction for smooth rotation of the vertical shaft 22.

The rollers 11, 12 and the guide shaft 13 are also antifrictional so that feeding is very exact and sensitive in 25 compliance with variation of thickness of the wire a. It will be noted that the pedestal 2 and sub-pedestal 2a

form a support means, the pedestal 2 carrying the rotary shaft 1 while the pedestal 2a carries the rotary shaft 13 and 6. The unit 10 forms a traveler means which engages the rotary feed shaft 6 in such a way as 30 to be freely movable axially therealong as well as angularly thereabout, this latter angular movement of the traveler means 10 being prevented only by engagement of the rollers 11 and 12 with the shaft 13. In this way the spring means formed by the spring 37 achieves a 35 substantially constant pressure for the sharp-edged roller 35 against the feed shaft 6.

As many embodiments of this invention may be made without departing from the spirit and scope thereof, it is to be understood that the invention includes all such modifications and variations as come within the scope of the appended claims.

What I claim is:

1. In a feed mechanism for a coil winder, support means, a rotary feed shaft carried by said support means, traveler means coacting with said feed shaft for moving freely therealong, said support means also supporting said traveler means for free movement parallel to said feed shaft, said traveler means carrying a swivel rod whose axis is perpendicular to the axis of said feed shaft and supporting said swivel rod for free swiveling movement about its axis, a feed roller having a relatively sharp peripheral edge engaging said feed shaft, said feed roller being operatively connected with said rod for swiveling movement therewith and having a neutral position where the axis of rotation of said roller is parallel to the axis of said feed shaft, said feed roller being located between said rod and feed shaft, a plurality of guide pulleys carried by said traveler means for guiding wire to a bobbin on which the wire is to be wound, said guide pulleys having grooved peripheries for receiving and guiding wire and including at least one guide pulley situated beyond said rod distant from said feed roller so that said rod extends between said one guide pulley and said feed roller, said one guide pulley being operatively connected with said rod for swiveling movement therewith and said peripheral groove of said one guide pulley and said peripheral

edge of said feed roller being located in a common plane which contains the axis of said rod with the latter axis extending perpendicularly across the axes of said one guide pulley and feed roller and with the latter axes being parallel to each other, said support means carrying an elongated guide shaft which is parallel to said feed shaft, said traveler means carrying rollers situated on opposed sides of and engaging said guide shaft to limit angular turning of said traveler means with respect to said feed shaft, said traveler means including 10 a pivoted carrier engaging said feed shaft at a side

thereof opposite from said feed roller and a spring means connected to said carrier and part of said traveler means for providing a substantially constant pressure between said feed roller and feed shaft, a handle being connected to said carrier for swinging the latter in opposition to said spring means to a position which will reduce the pressure between said traveler means and feed shaft for facilitating adjusting of said traveler means along said feed shaft.
